(57) **CLAIM**

I claim the ornamental design for a combined portable cigarette box and ashtray, as shown and described.

DESCRIPTION

Fig. 1.1 is a front view of an unfolded configuration of a combined portable cigarette box and ashtray showing my new design;

Fig. 1.2 is a back view of an unfolded configuration thereof;

Fig. 1.3 is right perspective view thereof;

Fig. 1.4 is an unfolded view of a cigarette box thereof;

Fig. 1.5 is an unfolded view of an ashtray thereof;

Fig. 1.6 is an exploded front view thereof; and

Fig. 1.7 is an exploded back view thereof.
